(57) **CLAIM**

The ornamental design for a dental tool, as shown and described.

DESCRIPTION

FIG. 1A is an isometric view of a first embodiment of the present invention taken from a front underside angle; FIG. 1B is an isometric view of the first embodiment taken from a side rear angle;

FIG. 2 is a top plan view of the first embodiment;

FIG. 3 is a side elevation view of the first embodiment;

FIG. 4 is a bottom view of the first embodiment;

FIG. 5 is a front view of the first embodiment;

FIG. 6 is a rear view of the first embodiment;

FIG. 7 is a side elevation view of the first embodiment with a variation of the extension member; and,

FIG. 8 is a side elevation view of the first embodiment with a second variation of the extension member.

The broken lines shown in the above figures are for illustrative purposes and form no part of the claimed design.
